UNITED STATES PATENT OFFICE.

ADELBERT M. BRAINARD, OF CHICAGO, ILLINOIS.

HYDROCARBON-GAS STOVE.

SPECIFICATION forming part of Letters Patent No. 255,245, dated March 21, 1882.

Application filed March 11, 1881. (No model.)

To all whom it may concern:

Be it known that I, ADELBERT M. BRAINARD, of Chicago, in the county of Cook and State of Illinois, have invented certain new and useful Improvements in Hydrocarbon-Gas Stoves; and I do hereby declare that the following is a full, clear, and exact description thereof, reference being had to the accompanying drawing, and to the letters of reference 5 marked thereon, which forms a part of this specification.

This invention relates to devices for generating and burning hydrocarbon gas or vapor in a so-called "hydrocarbon-gas stove;" and it 15 consists, first, in a special combination of the generator, main burner, and initial generator-heater, forming, as hereshown, a unitary structure; and, second, in the combination, with a generator of one burner in a hydrocarbon-gas 20 stove, of a tube leading from said generator to another burner, whereby a single generator may supply vapor to its own and also to one or more additional burners of the stove.

The nature of my invention will be hereinafter more fully and precisely set forth, and will 25 also be more definitely pointed out in the appended claims.

The accompanying drawing shows a burner embodying my present invention in central vertical section.

B represents a dishing or concave metal circular plate supported in the stove-top, (not here shown;) and F is a central metal cup depending from the plate B, in which cup are located 30 the several parts of the burner to be described.

G represents a pipe leading from the source of hydrocarbon supply; and G' is a vertical tubular branch therefrom, which directly supplies the burner. The "burner," as the term 35 is here broadly employed, comprises a generator, an initial generator-heater, and a burner-tube, (which latter is the tube from which the operative flame is emitted,) with their connections and valves or cocks.

H is the generator, of annular form, arranged 40 to surround and by its central passage, C², to form a part of the burner-tube, which is designated as a whole by the letter C. Said tube also comprises the bottom enlarged part, C', 45 provided with openings c c for the admission of air, and the correspondingly-apertured slide

or register C³, by which the amount of air admitted at c c is regulated. At the top of the tube C other openings, c' c', are provided, also for the entrance of air, and vapor or gas is supplied to the burner-tube at its lower end by the tube H', leading from the generator H. By reason of the admission of air at c' c' the vapor let on in force ignites within the tube-top about opposite c' c', and the flame emerges from the 55 tube in a solid body at its open top.

I is a horizontal metal plate, of circular form, surrounding the burner-tube C a short distance beneath the generator H. It has a slightly dishing or cupped upper surface and an inner 60 opening, I', preferably of considerable size, as shown. Said opening communicates with the dished surface of the plate through the annular slot i', and with the passage J within the stem G through the lateral passage i, closed 65 by the screw pressure-cock I². Liquid hydrocarbon being admitted to the surface of plate I by opening the cock I² is ignited, and the flame thereof heats up the generator H above it preparatory to the admission of liquid to the 70 latter for its vaporization and use in the main burner. Said plate I is therefore called the "initial" generator-heater. Having performed its office of heating the generator H in the first instance, its supply may be cut off by closing the 75 cock I²; but, on the other hand, if desired, it may be still kept alight, since the passage i is 80 wholly independent of that leading to the generator H.

The novel features of the devices above described or referred to have been set forth and claimed in another patent, for which application was filed of even date herewith. Only the special features of construction or combination are therefore claimed herein—namely, the 85 annular form of the generator H, its arrangement about the tube C, and its construction as forming a part of said tube, the combination, with the parts so arranged, of the cup or shield F, made central as to the plate B, for 90 the purpose of embracing the said parts, and certain special features in the construction of the plate I not elsewhere shown. Novel features not yet mentioned and not present in 95 said other patent are also claimed herein.

The generator H, as here shown, consists of a horizontal circular base-plate, H³, and the

dome-plate C⁴. Plate H³ has a central opening to admit the middle section of the tube C, and a marginal annular upturned flange, h², internally threaded to receive and secure the dome-plate. Said dome-plate consists of the two downwardly-projecting annular flanges c² and c³ and the upwardly-projecting flange c⁴. The outer flange, c², screws to the flange h², and the inner flange, c³, fits closely to plate H³ about its central opening. Flange c⁴ contains the openings c' and forms the mouth of tube C.

The initial heater plate or cup I surrounds the tube C loosely, and is upheld by the stem G', to which it is firmly secured. From the bottom of the chamber I a flange, i², rises about the tube C to the height of the elevated edge of the plate I, thereby preventing the liquid from escaping downward around said tube. When the plate I becomes heated the space I' becomes a generating-chamber, and if a flame is here kept continually alight, gas or vapor only will rise through the passage i'. As explained of the similar devices in said other patent, the surrounding shield F protects a small flame at I from being blown out, and such a flame may therefore be constantly maintained. Such a constant flame at I will obviously keep the generator H hot, so that the main burner may at any instant be supplied with gas by simply opening the cock H².

By reason of the ignition of the vapor within the top of tube C, as hereinbefore explained, the upper flange, c⁴, of the dome-plate C⁴ is exposed to great heat, and, being continuous with the walls of the generator-chamber, communicates its heat thereto. Said chamber, by its annular form and arrangement, may evidently be given considerable capacity, while by its construction and location as described it may be correspondingly heated. At the same time, by its arrangement below the flame it does not in the least interfere with such flame in its effect upon a superposed article being heated.

Having the advantages mentioned above as the result of its construction and arrangement with the burner-tube C, the generator H, it is found, may supply other burners than its own with vapor. For this purpose the tube T is shown as leading directly from the generator H, and as having the burner R provided with the support R' for an article to be heated at its extremity. By means of the cock r vapor is let onto the burner R, which may be at any time instantly lighted when the main burner is in operation, or when the generator H is properly heated. In a domestic stove this provision is one of great convenience and economy, since one burner is often kept in almost constant use, while a second or a third may be only briefly and occasionally but at the same time urgently needed. As here shown, the tube T is jointed at t to turn horizontally. The burner R may therefore be folded out of the way beneath the stove-top when not in use, though of course it may be

one of the fixed burners of the stove, standing permanently beneath a suitable hole in the stove-top.

By reason of the greater efficiency of the generator H when constructed and arranged as explained, hydrocarbon liquids of much heavier grades than have commonly been employed in this class of stoves may be vaporized and used with whatever advantage in safety there may be in the handling of such heavier grades by unskilled persons.

At h³ is seen a screw-plug, which stops a hole made in drilling the horizontal part of the passage h'. If desired, this plug may be lengthened to form a pressure-cock stopping said passage h'; or the tube H' may be elsewhere provided with a stop-cock of any suitable construction. When the passage supplying gas to the main burner is thus fitted with a cock between the generating-chamber and the burning-point the tube T, or a small corresponding tube leading from the generator, may be made to open beneath the generator or to direct its flame against the generator, so as to take the place of the heater I in keeping the generator hot. In that case the burner R would consist simply in the open end of the tube so arranged.

I am aware that an illuminating-burner has been supplied from a generator of a heating-burner, and also that a support for an article to be heated has been applied to an illuminating-burner of a house-lighting system. I do not therefore claim the elements of the following claim 4, except as they are combined as described in and with a self-generating gas-stove.

I claim as my invention—

1. In combination with the depressed plate B and central shield, F, beneath said plate, the burner-tube C, having an annular generator, H, about its upper end, and a generator-beater beneath the generator and within the shield, said generator and initial heater being suitably connected with the source of hydrocarbon supply, and, together with the shield F, arranged and operating substantially as described.

2. In the burner described, the annular generator H, composed of the base-plate H³ and the dome-plate C⁴, having the outer and inner flanges, c² and c³, joined with the base-plate, and the upper flange, c⁴, forming the mouth of the burner-tube, substantially as described.

3. In the burner described, the combination, with the burner-tube C and supply-stem G', of the initial heater-cup I, having the chamber I' and opening i' around the tube C, said cup being supported and supplied from the stem G', and surrounding the tube C by the rising flange i², substantially as described.

4. In a hydrocarbon-gas stove, the combination, with a main burner having a generator, of an additional burner, R, supported and supplied by a jointed tube leading from the main generator, and a support for an article

to be heated from said additional burner, forming part of the unitary stove structure, substantially as described.

5. In combination with the burner described, comprising the central tube, C, the generator H, and the initial generator-heater I, arranged as shown, the dished plate B and the cup F, arranged to embrace the parts C, H, and I, as set forth.

In testimony that I claim the foregoing as to my invention I affix my signature in presence of two witnesses.

ADELBERT M. BRAINARD.
